UNITED STATES PATENT OFFICE

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TEMPLE FOR DOUBLE-FABRIC LOOMS

Application filed July 22, 1929. Serial No. 380,132.

This invention relates to a temple for use with double fabrics and is particularly designed for use in a double shuttle loom of the weft replenishing type.

5 It is the general object of my invention to provide a temple by which both upper and lower fabrics may be guided and held from lateral contraction, while at the same time the unsevered weft ends of newly inserted 10 bobbins may have clear passage forward between the temple rolls.

To the attainment of this object, I provide a separator or guiding member between the upper and lower temple rolls, so disposed 15 and supported that weft ends may pass freely over and under said member as they work forward past the temple rolls.

20 My invention further relates to arrangements and combinations of parts which will be hereinafter described and more particularly pointed out in the appended claims.

A preferred form of the invention is shown in the drawings in which

25 Fig. 1 is a plan view of a portion of a loom having my improved temple mounted thereon;

30 Fig. 2 is a side elevation of the temple, taken along the line 3—3 in Fig. 2; Fig. 1;

Fig. 3 is a sectional front elevation of the temple, taken along the line 5—5 in Fig. 2;

Fig. 4 is a side elevation, looking in the direction of the arrow 4 in Fig. 3; and

35 Fig. 5 is a sectional front elevation, taken along the line 5—5 in Fig. 2.

Referring to the drawings, I have shown a part of a loom frame 10 on which a temple stand 11 is secured. A temple bar 12 is yieldingly slid able in the stand 11 in the usual manner and extends rearward toward the fell of the cloth.

40 At its rearward end, the bar 11 is offset downward and rearward, as indicated at 14, and is provided with a pair of lower temple rolls 16 of the usual construction. A similar 45 pair of upper temple rolls 18 are mounted on a frame member 20 secured to the temple bar 12 by a bolt 22. The offset lower portion 14 of the bar 12 and the frame member 20 are 50 spaced apart vertically to provide a free

passage 24 to a point forward of the temple rolls, for a purpose to be described.

A guiding and separating member 30 is also secured to the bar 12 by the bolt 22 and may also be fixed in relation thereto by a pin 55 or stud 32. The member 30 extends freely rearward between the rolls 16 and 18 and is of such contour that the upper and lower fabrics are separated and guided closely adjacent the peripheries of the upper and lower 60 rolls.

A bracket 40 is secured to the bar 12 by the bolt 22 and is also secured to the offset member 14 by the bolt 42 (Fig. 2) which supports the forward lower roll 16 and to the upper frame member 20 by the bolt 44 by which the forward upper roll 18 is secured to said frame member. The bracket 40 is thus firmly held in position and also acts to positively determine the spaced relation 70 of the upper frame member 20 from the offset portion 14 of the bar 12.

The bracket 40 is provided with a laterally extended or table portion 46 having its rear edge portion curved downwardly, as 75 indicated at 48 in Fig. 2. A plurality of weights 50 are loosely mounted on a stud 52 secured in the table portion 46.

The temple thus described is particularly adapted for use in a double shuttle loom in which the weft ends of the bobbins are tied together in pairs before the bobbins are placed in the magazine. When one bobbin of a pair is transferred, the weft end W remains attached to the other bobbin left in the 80 magazine, as indicated in Fig. 1, and is gradually drawn under the sectional weight 50 by the forward feed of the cloth. During this forward feed, the weft end W extends outward from the selvage of the cloth and 85 moves freely forward through the open passage 24 previously described.

Such forward movement causes the weft end to be clamped by the weight 50, after which the weft is broken between the weight 90 and the selvage. The open passage 24 extends forward in the temple beyond the point necessary for drawing the weft end under the weight 50.

I am thus able to firmly hold and stretch

both the upper and lower fabrics by the temple rolls 16 and 18, while at the same time permitting free forward movement of the weft end W to clamping and breaking position.

Having thus described my invention and the advantages thereof, I do not wish to be limited to the details herein disclosed, otherwise than as set forth in the claims, but what I claim is:—

1. In a loom for weaving double fabric, a temple frame, a pair of upper temple rolls and a pair of lower temple rolls supported by said frame, and a rearwardly extending guiding and separating member positioned between said upper and lower rolls and supported entirely by said frame at a point forward of said rolls.
2. In a loom for weaving double fabric, a temple frame, a pair of upper temple rolls and a pair of lower temple rolls supported by said frame, and a guiding and separating member positioned between said upper and lower rolls, supported by said frame and extending freely rearward between said rolls.
3. In a loom for weaving double fabric, a temple frame, a pair of upper temple rolls and a pair of lower temple rolls supported by said frame, and a guiding and separating member positioned between said upper and lower rolls and supported by said frame, said rolls and said separating member being disposed to provide a free passage for the weft end extending outward from a fabric passing through said temple.

In testimony whereof I have hereunto affixed my signature.

RICHARD G. TURNER.
